BATTERY LIFTER

Chester A. Sumter, Rte. 11, Knoxville 18, Tenn.
Filed May 22, 1961, Ser. No. 111,667
5 Claims. (Cl. 294—15)

This invention relates to improvements in a carrier adapted for the lifting and transportation of storage batteries and the like.

The primary object of this invention is the provision of an improved battery carrier having means to facilitate expeditious application directly upon the terminal posts of the storage battery in order that it can be lifted and transported with ease and without possibility of slipping from the posts.

In my Patent 2,435,549, I have shown a battery carrier having the general characteristics of the present battery carrier. The present carrier is less expensive to make and just as durable, including a lifting member which may be more easily operated to adjust it lengthwise of the supporting handle.

Other objects and advantages of this invention will be apparent during the course of the following detailed description.

In the accompanying drawing, forming a part of this specification wherein similar reference characters designate corresponding parts throughout the several views:

FIGURE 1 is a perspective view of the improved battery carrier.

FIGURE 2 is a perspective view showing the application of the improved battery carrier upon a conventional three cell battery.

FIGURE 3 is a view showing the association of a tong type lifting member of the carrier; in full lines showing its application to a handle and in dot and dash lines showing how the lifting member can be opened to adjust it lengthwise of the handle.

FIGURE 4 is a fragmentary side elevation of the carrier handle at one end, partly in section, and showing another lifting member attached to the handle.

FIGURES 5 and 6 are cross sectional views taken substantially on the respective lines 5—5 and 6—6 of FIGURE 1.

In the drawing, wherein for the purpose of illustration is shown only a preferred embodiment of the invention, the letter A may generally designate the improved battery carrier. It is adapted to be attached to either short batteries B of the three cell type, or longer batteries of twelve cells, etc.

The improved battery carrier A preferably comprises an elongated member 10 which may be conveniently referred to as the handle, preferably formed of wood although not limited to such material. In cross section it is square or polygonal although if desired it may be suitably shaped to conform to the hand of the user. The handle 10 is provided with a series of transverse openings 11 therein which are relatively spaced therealong. The openings are transversely horizontal and extend from side to side of the handle 10.

The carrier A at one end of the elongated supporting member 12 has a fixed terminal post attaching lifting member 20. Preferably it is made of wire and includes a post inserting looped portion provided with side strands or portions 22 and 23 which in side elevation at their portions extending beyond the handle are rather V-shaped, as shown in FIGURE 4. The sides 22 and 23 are connected by a bight portion 24 and they relatively converge to the bight portion 24; the inner edges of the sides 22 and 23 and the bight 24 are provided with chisel-type edges 25, such as shown in FIGURE 5. The wire strand portions 22 and 23 of the lifting member 20 extend for a short distance beneath the handle 10 as shown in FIG-

2

URE 4 and then are extended upwardly in right angled relation at 30 through passageways 31 vertically provided in the handle 10, and at their upper ends they are crimped at 32 to provide heads for holding the lifting member 20 against movement or detachment. In other words the member 20 is rigidly fixed on the handle 10 in the position shown.

A second lifting member 35 is provided, which can be detachably mounted upon the handle 10 and applied in 10 any of the openings 11 longitudinally of the handle in order to relatively space the lifting members 20 and 35 to suit the length of the battery.

The member 35 is of tong-like construction comprising a pair of legs 40 and 41 which are relatively movable and 15 which at their outer ends are provided with convergent portions 42 and 43 terminating in a bight 44 which connects them. The inner edges of the bight portions 42 and 43 and bight 44 are sharpened to chisel edges, as shown at 45 in FIGURE 6. The legs 40 and 41 remote from

20 the bight 44 are provided with obliquely angled portions 47 and 48, which cross each other in X shaped relation, and which at their outer ends are provided with parallel attaching portions 49 and 50 respectively having at their inner ends right angled handle inserting prongs 51 and 52 25 respectively. The lifting member 35 is formed of wire and the bight 44 resiliently connects the legs 40 and 41 in order that the prongs 51 and 52 normally move toward each other and seat in the opposite ends of an opening 11, as shown in full lines in FIGURE 3 of the drawings.

30 However, by pressing the side portions 40 and 41 together the bight 44 is stressed in order that the attaching portions 49 and 50 as shown in the dot and dash lines in FIGURE 3 of the drawings can be moved apart whereby the prongs 51 and 52 will move out of the opening 11 and the lifting member 35 can then be moved to any position along the handle 10 for insertion in any of the openings 11, to suit the spaced relation of the battery terminal posts.

The battery B is provided with a casing structure 70 having cells 71, the end ones of which are provided with 40 terminal posts 72 normally tapered upwardly.

Referring to the use of the battery carrier A, the lifting member 35 is adjusted along the handle to the position which suits the spacing of the battery terminal posts 72. Since the lifting member 20 is fixedly attached to the handle 10, it can be applied to one of the posts 72; the sharp edges 25 of the convergent sides 22 and 23 and bight 24 penetrating the posts 72. Thereafter the lifting member 35 is similarly applied to the other terminal post. The operator then grasps the handle 10 between the lifting members 20 and 35 if the battery is long or the end of the handle if the battery is short as shown in FIGURE 2, and merely lifts upwardly. The battery carrier is then attached to the battery and the latter can be moved to a desired location.

55 The normal resilient action of the lifting member 35 at the bight portion 44 brings the prongs 51 and 52 into position for insertion into an opening 11, and merely by squeezing the sides 40 and 41 of the lifting member 35 together the operator moves the prongs 51 and 52 out of 60 the opening 11. The lifting member 35 can then be moved to any desired location along the handle 10 for insertion of its prongs into another opening 11. The spring action of the sides 40 and 41 normally causes them to tighten at the bight end upon the battery post.

65 Various changes in the shape, size and arrangement of parts may be made to the forms of invention herein shown and described, without departing from the spirit of the invention or scope of the claims.

I claim:
70 1. In a carrying appliance for lifting and carrying storage batteries and the like the combination of an elongated rigid supporting handle having a series of relatively spaced

transverse openings therein which open at opposite sides of the handle, a lifting member connected to one end of the handle and projecting endwise therefrom and having means thereon for gripping a battery terminal post, and a second lifting member having means thereon for releasable connection with any of the series of openings of the handle, said second lifting member comprising a pair of normally closing spring actuated arms provided at their outer ends with a battery post attaching bight and at their inner ends with means to releasably engage in the openings of the handle.

2. In a carrying appliance for lifting and carrying storage batteries and the like the combination of an elongated rigid supporting handle having a series of transverse openings therein at relatively spaced distances along said handle opening at opposite sides of the handle, a lifting member rigidly connected at one end to the handle and extending endwise thereof and comprising a pair of side portions which are rigidly connected at their inner ends to the handle and at their outer ends are provided with a connecting bight portion, said sides adjacent the bight portion converging towards each other and their facing surfaces and the inside of the bight being provided with sharpened post engaging chisel edges, and a second lifting member having relatively movable elongated side portions with means to releasably engage in the openings at opposite sides of the handle and at the outer ends thereof being provided with convergent side portions and a bight connection therefor, the inner surfaces of said side portions and bight of the second member having chisel type terminal engaging edges.

3. In a carrying appliance for lifting and carrying storage batteries and the like the combination of an elongated rigid supporting handle having longitudinally thereof a series of lateral openings at opposite sides thereof, a wire lifting member rigidly connected to the carrying member at one end of the handle and extending endwise thereof and including relatively spaced side portions which converge at their outer ends and are connected by a bight portion, the inner sides of said convergent portions and inner side of the bight being sharpened for battery post engagement, and a second lifting member of tong-like construc-

tion comprising a pair of leg portions connected together at one end of the lifting member and at the opposite end being disconnected, said leg portions normally being biased to be urged resiliently towards each other at their disconnected ends and having means at their non-connected ends for engaging in the openings of the handle, the connected ends of said leg portions being relatively convergent and adapted to engage a battery post for gripping purposes.

4. In a carrying appliance for lifting and carrying storage batteries and the like, which have upstanding terminal posts thereon, the combination of an elongated rigid handle having side opening apertures at spaced intervals along the opposite sides thereof, a lifting member connected to the carrying member at one end of the handle having means thereon to engage and grip a battery post, and a second lifting member comprising a pair of spring biased elongated side portions which at one end of each are connected by a bight portion and at the other ends thereof are provided with inturned non-connected ends forming prongs, the biasing of said side portions being such as to normally cause said prongs to move together, the side portions at the bight portion being convergent and adapted to grip a post of the battery with the spring biasing of said arms normally urging the convergent sides of the bight portion into battery post clamping positions.

5. A battery carrying appliance as described in claim 4 in which the inner facing edges of the convergent portions are sharpened for biting into the material of a battery post.
